DESIGN FOR LEATHER

Richard Bernheim, New York, N. Y., assignor to
R. Neumann & Company, Hoboken, N. J., a
corporation of New Jersey

Application March 21, 1935, Serial No. 55,981

Term of patent 3½ years

To all whom it may concern:

Be it known that I, Richard Bernheim, a citizen of the United States, residing at 55 East 72nd Street in the city of New York, county and State of New York, have invented a new, original, and ornamental Design for Leather, of which the following is a specification, reference being had to the accompanying drawing forming a part thereof.

The figure of the drawing is a plan view of a

piece of leather embodying my design which consists of a double series of wavy lines complementary to each other and perforations in the material between the points where the series of wavy lines touch each other, these perforations being approximately quadrilateral in form.

I claim:—

The ornamental design for leather substantially as shown and described.

RICHARD BERNHEIM.
